James C. Ledbetter

UNITED STATES PATENT OFFICE.

JOHN NEWMANN, OF BROOKLYN, NEW YORK.

ENGINE CRANK SHAFT.

Application filed June 30, 1921. Serial No. 481,499.

To all whom it may concern:

Be it known that I, JOHN NEWMANN, a citizen of the United States, residing at Brooklyn, in the county of Kings and State of New York, have invented certain new and useful Improvements in Engine Crank Shafts, of which the following is a specification.

This invention relates to internal combustion motors and more particularly to improvements in the construction and operation thereof with a view of generally improving the efficiency of this class of engine. The invention especially relates to crank shafts.

The primary object is to produce an internal combustion motor comprising a combination of new features which makes this engine highly adaptable for aeronautical and automotive purposes.

Furthermore it is an object to produce an engine of the radial cylinder type having a plurality of cylinders grouped about a common crank case, and having a crank shaft with a single crank-throw common to all the piston connecting rods. In the present invention and engine design, I employ an engine crank shaft construction similar to that shown in my copending application Serial Number 353,374 filed January 22, 1920, and entitled Crank and pitman connection, except however I have improved the crank shaft design in a manner as later described.

In producing this invention, I have in view certain objects such as to make an improved combination air cooled and vapor cooled engine cylinder so that I secure the useful effects of this cooling method; and it is an object to utilize the heat of the cylinder head to raise the temperature of the fuel mixture which produces the double function and advantage of simultaneously cooling the engine and preheating, drying and thoroughly vaporizing the gaseous fuel mixture prior to its combustion in the cylinder.

Likewise it is an object to produce an engine having an improved valve and head structure of such design as will allow of a rapid discharge the exhaust gases and inflow of the intake gases, and which head is so coordinated with the aforesaid cooling

system as to adequately cool the cylinder head parts and engine.

The accompanying drawings show the principle and an embodiment of my invention, and though I have illustrated and described a preferred form of engine construction and operation, as well as crank shaft improvements, I claim a right of protection as to all such changes as obviously come within the scope of my invention.

Figure 1 is a sectional fragmentary view of an engine equipped with my improved crank shaft.

Figure 2 shows the engine crankshaft removed from the engine; and Figure 3 shows an improved counterbalance weight removed from the crank shaft.

Figure 4 shows a connecting rod and bearing assembly forming a part of this invention.

Referring now more particularly to the drawings, wherein like numbers are used to indicate like parts, for a detailed description of the invention, there is shown a plurality of cylinders 10 radially mounted on a crank case 11. A piston 12 is confined in each cylinder and has a connecting rod 13 with an integral bearing housing 14; and this bearing housing is unitary in construction which avoids certain difficulties experienced with the presently used two-piece connecting rod bearing housing. With particular reference to Figure 4, it is pointed out that the housing 14 is made with equal distantly spaced holes 15, to which the other connecting rods of the engine are secured in order that all the connecting rods be connected in common to a single bearing housing. The bearing housing is provided with bushings 16 which are removed and placed in the housing in a novel manner as later described. The bearings or bushings housing 14 is cut out, as shown at 17, so that the connecting rod may be easily placed on the crank pin of the crank shaft.

The improved crank shaft comprises a shaft 20 having the webs 21 with a crank 22 disposed therebetween. One of the webs 21 is made with a removable cap section 23, which, when in position, provides an abut-

ment shoulder adjacent the crank-pin bushing, and which, when removed, renders possible the removal of the bearing bushing. One of the crank webs 21 is preferably made with an integral counterbalance weight 24; and the other web is provided with a removable counterbalance weight 25. This arrangement and construction of parts, as will be seen, renders it possible to remove and replace the connecting rod upon the crank shaft.

The counterweight 25 is made integral with a plate 26 which laps over and partly surrounds the web 21. In fact, the plate is made as shown in Figure 13, with a socket 27 and this socket is made the counterpart of the web, so that the web is received within and snugly fits into the socket. Shoulders 28 are made on the counterweight adjacent the socket so that the back face of the web rests against the shoulders making a substantial and well fitting construction. The plate is made with a hub 29 which fits over the shaft 20 to center and hold the removable counterweight 25 in secure position and also provide a seat for the crank shaft bearing. A nut is screwed on a threaded portion of the crank shaft to lock the counterweight on the shaft and to secure the crank bearing on the hub. A screw 30 is passed through the crank-pin 22 and secures the cap 23 and counterweight 25 in position.

In assembling and fitting up the connecting rod and crank shaft, the cap and counterweight 25-26 are removed from the crank shaft, and having removed the bushings 16 from the connecting rod housing 14 the connecting rod 13-14 is slipped on shaft and over the rounded off corner 32 of the crank web 21 until the housing 14 is in place on the crank pin 22. In accomplishing the assembly of the crank shaft and connecting rod, the mechanic so moves the connecting rod that the hollowed out portion 17 slips past the corner 32 of the crank pin. The hollowed out part 17 makes it possible to construct a comparatively small housing 14 with a small bore, and yet pass it over the rounded end of the crank pin. The cap 23 and counterweight 25 are now placed in position and screw 30 is tightly set in position to secure these parts together upon the crank.

In the adjustment or replacement of the bushings 16, the mechanic, having removed the cap 23, and worn bushing, places one end of the replacement bushing upon the exposed end of the crank pin 22 and thrusts the half section bushing forward until it is confined in position between the pin 22 and housing 14. He then turns the half section bushing around on the bottom side of the pin 22; and thereafter the other half section of the bushing is forced into position. The cap 23 is then replaced which forms an abutment shoulder at the foot of

the pin and at the end of the bushings to hold the bushings in position. This design and function of the parts make for the convenience and quick repair and adjustment of conection rod bearings, and the shimming 70 of bushings to take up wear is accomplished in a similar manner.

What I claim is:

1. A crank shaft for engines comprising a shaft, a crank-throw made on the shaft, a 75 crank-pin made a part of the crank-throw and provided with a longitudinal bore made there-through, a removable counterweight disposed on the shaft and lying adjacent the crank-pin, and a screw disposed through the 80 bore to secure the counterweight.

2. A crank shaft for engines comprising a shaft, a crank-throw made on the shaft, a crank-pin made as a part of the crank-throw, a cap disposed over one end of the crank-pin 85 and forming a continuation of the crank-throw, a counterweight disposed on the shaft and forming a continuation of the crank-throw, and a screw employed to secure the cap and counterweight on the shaft in locked 90 position against the crank-pin.

3. A crank shaft for engines comprising a shaft, webs made on the shaft to make a crank-throw, a crank-pin disposed between the webs to complete the crank-throw, one 95 of the said webs being terminated flush with the outer surface of the crank-pin for the purpose of admitting and removing connecting rod bearing bushings, a cap to complete the web and form an abutment adjacent the crank-pin, and a screw for securing the cap in position.

4. A crank shaft for engines comprising a counterbalance weight, a plate integrally formed with the counterbalance weight, and a hub made a part of the plate and counterbalance weight to hold the removable counterweight on the shaft, and accommodate the shaft bearing.

5. A crank shaft for engines comprising a 110 shaft having a threaded portion, a web made on the shaft, a crank pin disposed between the webs, a counterweight made separately of the crank shaft and removable therefrom to facilitate the assemblying of a connecting rod and bearing on the crank pin, a hub made on the removable counterweight and disposed on the shaft to form a seat to receive a crank shaft bearing, and a nut screwed on the threaded crank shaft to secure 115 the counterweight in fixed position.

6. A connecting rod and crank shaft assembly for engines, comprising a shaft having a crank-throw, a crank-pin forming a part of the crank-throw, a counterbalance weight removably secured upon the crank shaft, a plate integrally formed with the counterweight and extending around the web to form an abutment shoulder on the crank-pin, a connecting rod having a unitary hous- 125 130

ing capable of being placed in position upon the crank-pin when the counterweight is removed from the shaft, and a means for securely anchoring the counterweight on the 5 crankshaft.

7. A connecting rod and a crank shaft assembly for engines as defined in claim 6, in which the bearing housing of the connecting rod is made with a cut out section in 10 order that the connecting rod may be more readily placed upon and removed from the crank-pin.

8. A connecting rod and crank shaft assembly for engines, comprising a shaft having crank-throw webs, a crank-pin forming a part of the crank-throw, a counter-balance weight removably secured upon the crank shaft, a plate integrally formed with the

counterweight and extending alongside of the crank-throw forming abutment shoulders 20 on the crank-pin, a connecting rod having a housing capable of being placed in position upon the crank-pin when the counterweight is removed from the shaft, means for securely anchoring the counterweight on the 25 crankshaft after the connecting rod is in place, said connecting rod housing made with a cut out portion to enable the connecting rod bearing to be placed on the crank-throw, and a removable cap section carried on the 30 web opposite the removable counterweight.

In testimony whereof I hereunto affix my hand and seal in the city of New York, borough of Manhattan and State of New York, this 29th day of June, 1921.

JOHN NEWMANN.
